CLAIM

The ornamental design for a set of collapsible crates, as shown and described.

DESCRIPTION

FIG. 1 is a perspective view of a set of collapsible crates showing my new design, the insert removed from the set for clarity of disclosure;

FIG. 2 is a front view thereof;

FIG. 3 is a back view thereof;

FIG. 4 is a top view thereof;

FIG. 5 is a bottom view thereof;

FIG. 6 is a left-side view thereof;

FIG. 7 is a right-side view thereof;

FIG. 8 is a perspective view of a set of collapsible crates, showing the insert removed from the set for clarity of disclosure;

FIG. 9 is a front view thereof;

FIG. 10 is a back view thereof;

FIG. 11 is a top view thereof;

FIG. 12 is a bottom view thereof;

FIG. 13 is a left-side view thereof;

FIG. 14 is a right-side view thereof;

FIG. 15 is a perspective view of a set of collapsible crates, showing the collapsible crates fitted into an unclaimed outer crate;

FIG. 16 is a front view thereof;

FIG. 17 is a back view thereof;

FIG. 18 is a top view thereof;

FIG. 19 is a bottom view thereof;

FIG. 20 is a left-side view thereof; and,

FIG. 21 is a right-side view thereof.

The dash-dot-dash lines shown on the bottom of the crate represent fold lines and the short broken lines on the surface of the crate represent stitching, all forming part of the claimed design.

The broken line showing of the crate in FIGS. 15-21 is included for the purpose of illustrating environmental structure and forms no part of the claimed design.
